HANDLE UNIT FOR A DRIVING MACHINE

Werner Schafroth, P.O. Box 247, Herrin, Ill.

Filed June 28, 1965, Ser. No. 85,942

Term of patent 14 years

(Cl. D54—14)

FIG.1

FIG.2

FIG.3

FIG.4

FIG.5

FIG. 1 is a top plan view of a handle unit for a driving machine showing my new design,

FIG. 2 is a side elevational view thereof,

FIG. 3 is a front elevational view thereof,

FIG. 4 is a rear elevational view thereof, and

FIG. 5 is a perspective view of the side opposite to that shown in FIG. 2.

The essential features of my design reside in the portions shown in solid lines.

I claim:

The ornamental design for a handle unit for a driving machine, substantially as shown and described.
